INVENTOR:

Emil W. Schill,
BY Drake & Co. ATTY'S.

UNITED STATES PATENT OFFICE.

EMIL W. SCHILL, OF NEWARK, NEW JERSEY, ASSIGNOR OF ONE-HALF TO
ANDREAS BECKER, OF SAME PLACE.

JEWELRY.

SPECIFICATION forming part of Letters Patent No. 434,405, dated August 12, 1890.

Application filed November 14, 1889. Serial No. 330,320. (No model.)

To all whom it may concern:

Be it known that I, EMIL W. SCHILL, a subject of the Emperor of Germany, residing at Newark, in the county of Essex and State of

5 New Jersey, have invented certain new and useful Improvements in Jewelry; and I do hereby declare the following to be a full, clear, and exact description of the invention, such as will enable others skilled in the art to which
10 it appertains to make and use the same, reference being had to the accompanying drawings, and to letters of reference marked thereon, which form a part of this specification.

The object of this invention is to reduce the
15 cost of constructing jewelry; and it consists in the arrangement and combinations of parts, substantially as hereinafter set forth.

Referring to the accompanying drawings, in which like letters indicate corresponding
20 parts in each of the several figures, Figure 1 is a face view, and Fig. 2 is a side view, of a finger-ring embodying my invention. Fig. 3 is a plan of the same. Fig. 4 is a section taken on line *x*, and Fig. 5 shows a section of a cramp
25 of peculiar construction. Figs. 6 and 7 are views of a "gallery" or setting, and Fig. 8 is a section showing a modification.

In said drawings, *a* indicates the body of the finger-ring or other article of jewelry.
30 *b* is a setting having a series of cramps *c* of ordinary construction, and *d* are hollow-wire cramps soldered on the setting.

e are stones fixed between the cramps, and *f* are stones fixed on the hollow wires.
35 *g* is a plate soldered at the bottom of the setting, and *i* is a central hollow wire which extends up through the central chamber in the setting and serves to receive a central stone *h* and as a central support for the series
40 of stones *f*.

The setting may be made as in Fig. 8, where *j* indicates a blank struck up or formed of sheet metal, in which a shoulder *k* is formed, having a recess *l* on the side to receive the
45 stone, and having a flange *m*, on which a gallery is soldered, the latter having a series of

hollow-wire cramps *d*, Fig. 7, between which and the recessed shoulder the larger stones are held and on the top of which the smaller stones are set.

50 In carrying out the invention I first provide a setting *b*, of any ordinary construction, which may be made by bending the gallery (shown in Fig. 6) to the form of a continuous band or ring. Then to the bottom of the ring thus formed is soldered the plate *g*, forming what may be held to resemble a cup. To the upper edge of the gallery is soldered hollow-wire cramps, which may be made to alternate with solid cramps *c*. I next solder in the center 6c of the cup-shaped receptacle a central hollow cramp, after which the larger stones *e* are fastened between the cramps, and on the extremities of the hollow wire are fastened the smaller stones, thus producing a beautiful 65 effect at a reduced cost.

Having thus described the invention, what I claim as new is—

1. In an article of jewelry, a setting having hollow wires alternating with solid cramps, 70 substantially as set forth.

2. In an article of jewelry, the combination of the setting, a plate *g*, soldered to the bottom edge thereof, and hollow-wire cramps soldered on the upper side thereof, substantially 75 as set forth.

3. The finger-ring, combining with the body *a*, a ring-like setting having a bottom plate soldered to the inner edge thereof, a series of hollow-wire cramps soldered to the upper 80 edge of the setting, and a central hollow wire fastened to said plate, stones interposed between said cramps, and stones seated on said hollow wires, substantially as and for the purposes set forth.

85 In testimony that I claim the foregoing I have hereunto set my hand this 28th day of October, 1889.

EMIL W. SCHILL.
